UNITED STATES PATENT OFFICE.

DANIEL NACHTIGAL, OF HIBBING, MINNESOTA.

CAN OPENER.

Application filed June 29, 1925. Serial No. 40,427.

My invention is a combination can and bottle opener, and its principal object is to provide a device which can be used for either opening a can or tearing a bottle cap from a bottle.

A further object of the invention is to provide an implement of this character which can be readily adjusted to cut a can top of various diameters and which will 10 cut the can top in a quick and efficient manner.

Still another object of the invention is to provide a combined can and bottle-cap remover including a shank provided with 15 a slideable element which is so constructed as to either cut the can or disengage a bottle cap from a bottle.

With the preceding and other objects and advantages in mind, the invention consists 20 in the novel combination of elements, constructions, and arrangements of parts and operations to be hereinafter specifically referred to, claimed, and illustrated in the accompanying drawings wherein:

25 Figure 1 is a top plan view of the device associated with a can, the can being shown in broken lines;

Fig. 2 is a longitudinal sectional view taken on line 2—2 of Fig. 1;

30 Fig. 3 is a side elevation of the device used as a bottle-cap remover;

Fig. 4 is an end elevation of the device; and

Fig. 5 is a perspective of the cutter and 35 bottle-cap engaging hook embodied in the invention.

Referring to the drawings in detail wherein corresponding characters of reference indicate corresponding parts throughout the 40 several views, the numeral 5 designates a shank provided with a handle 6 arranged across one end and a can piercing element 7 at its opposite end. A novel cutting blade and bottle-cap engaging hook is provided 45 and includes a rectangular sleeve 10 slidably arranged on the shank 5 and having one end formed with a plurality of laterally extending fingers which are arranged in cruciform relation. One pair of these fingers 50 11 are L-shaped in cross-section as shown in Fig. 5, while the uppermost finger terminates in a lift 12 to engage a bottle cap as shown in Fig. 3. When it is

desired to remove a bottle cap the handle 5 is placed in position as shown in Fig. 3 with 55 the lift 12 engaged beneath the cap and upon rocking of the handle the cap will be lifted from its seat.

Extending at right angles to the shank 5 and slidably mounted thereon is a can cutting blade 13 having a shank 14 extending at right angles thereto, the latter being interposed between the upper face of the shank 5 and the upper wall of the sleeve 10 and terminating in an upstanding flange 14' 65 which engages the rear end of the sleeve and holds the shank 14 in the sleeve.

This blade 13 is spaced from the forward end of the sleeve 10 by the ends of the L-shaped in cross-section fingers 11. 70

In the use of the device as a can opener, the element 7 is pierced through the center of the can top and the cutter 13 arranged to engage the can at the desired point. This disposes the lower finger 11 against the side 75 of the can thereby holding the knife cutter against displacement while the device is being operated.

While I have shown and described the preferred embodiment of the invention, I 80 desire to have it understood that changes in the construction and arrangement of parts may be made without departing from the spirit of the invention or the scope of the subjoined claim. 85

What is claimed is:

A can opener of the character described comprising a shank, a sleeve slidably mounted thereon, a pair of laterally disposed fingers extending from said sleeve, a finger depending from said sleeve, a knife having a shank disposed between the sleeve and the shank first mentioned, and said fingers first mentioned engaging the knife to space the same from said sleeve finger second mentioned, an upstanding flange formed on the shank of the knife and engaging the rear edge of the sleeve to associate said knife with said sleeve so that they may be moved in unison, a can piercing element secured to one end of the shank first mentioned and a handle arranged across the opposite end of the shank first mentioned. 95 100

In testimony whereof I affix my signature,

DANIEL NACHTIGAL.
